UNITED STATES PATENT OFFICE

113,403

DESIGN FOR A COMBINED CAMERA AND GRIP THEREFOR

Louis T. Stroever, Piedmont, Calif.

Application August 8, 1938, Serial No. 79,181

Term of patent 14 years

To all whom it may concern:

Be it known that I, Louis T. Stroever, a citizen of the United States, residing at 28 Olive Street, in the city of Piedmont, county of Alameda, and State of California, have invented a new, original, and ornamental Design for Combined Camera and Grip Therefor, of which the following is a specification, reference being had to the accompanying drawing, forming part thereof, in which:

Figure 1 is a view in side elevation of a combined camera and grip therefor embodying my invention;

Figure 2 is a rear view of the device shown in Figure 1, the view finder shown in Figure 1 being in closed position; and

Figure 3 is a plan view of the grip portion.

The dominant features of the design reside in the grip shown in full lines in the drawing.

I claim:

The ornamental design for a combined camera and grip therefor, as shown and described.

LOUIS T. STROEVER.
